Primary Examiner — Amy C Wierenga*(74) Attorney, Agent, or Firm* — Stetina Brunda Garred and Brucker(57) **CLAIM**

The ornamental design for piston device for a valve, as shown and described.

DESCRIPTION

FIG. 1 is a perspective view of piston device for a valve; FIG. 2 is a top view of FIG. 1; FIG. 3 is a bottom view of FIG. 1; FIG. 4 is a right side view of FIG. 1; and, FIG. 5 is a left side view of FIG. 1.

The broken lines shown in the drawings depict portions of the piston device for a valve that form no part of the claim.
